*Primary Examiner—A. Hugo Word**Assistant Examiner—Celia A. Murphy**Attorney, Agent, or Firm—Hugh E. Smith***[57]****CLAIM**

The ornamental design for a combination jacket and trousers for a hunter, as shown and described.

DESCRIPTION

FIG. 1 is a front elevational view of a combination jacket and trousers for a hunter showing my new design;

FIG. 2 is a rear elevational view thereof;

FIG. 3 is a left side elevational view thereof;

FIG. 4 is a right side elevational view thereof;

FIG. 5 is a top plan view thereof; and

FIG. 6 is a bottom plan view thereof, the lower tabs shown wrapped around the ankles; and,

FIG. 7 is an isometric view thereof.

The broken lines shown in FIGS. 1, 3, and 4 are understood to represent conventional stitching.

FIG. 1

FIG. 2

FIG. 3

FIG. 4

FIG. 5

FIG. 6
